[57] CLAIM

The ornamental design for an electric switch for a toy
train set, as shown and described.

DESCRIPTION

FIG. 1 is a top perspective view of the electric switch
for a toy train set showing my new design;

FIG. 2 is a front elevational view thereof;

FIG. 3 is a side elevational view thereof, the other side
being identical;

FIG. 4 is a rear elevational view thereof;

FIG. 5 is a top plan view thereof; and,

FIG. 6 is a bottom plan view thereof.

FIG. 6

FIG. 4

FIG. 3

FIG. 2

FIG. 5

FIG. 1
